AUTOMATIC TOOL BLOCK

Secondo L. Casella and Morris G. Himoff, New York, N. Y., assignors to Morey Machinery Co., Inc., New York, N. Y., a corporation of New York

Application September 4, 1943, Serial No. 501,212

5 Claims. (Cl. 29—49)

This invention relates to automatic tool block. An object of this invention is to provide an automatic tool block adapted to be mounted on a cross slide of a lathe and having highly improved means for rotating, locking and clamping an indexable tool holder.

A further object of this invention is to provide in a device of the character described, an indexable tool holder, means to clamp the holder, a locking pin to lock the holder in each of a plurality of index positions, a handle, and means operable upon rotation of the handle to sequentially unclamp the holder, release the locking pin, rotate the holder to a new index position, lock the locking pin, and clamp the holder.

Yet a further object of this invention is to provide a device of the character described, in which the release of the clamp and locking pin, the rotation of the holder and subsequent locking of the locking pin and actuation of the clamp is accomplished by rotation of the handle substantially one complete turn, either clockwise or counterclockwise.

Yet another object of this invention is to provide a brake clamp for an indexable member and highly improved means to actuate the clamp and produce a tight grip by means of a relatively small movement of the actuating part.

Still a further object of this invention is to provide a highly improved device of the character described including gearing for rotating the indexable tool holder 90° in either direction each time the handle is rotated through substantially one turn.

Yet a further object of this invention is to provide a device of the character described having means to provide a lost motion at the beginning and end of each turn of the handle before operation of the device begins, whereby to make it unnecessary to rotate the handle through any exact angle, thereby facilitating operation of the device.

A still further object of this invention is to provide in a device of the character described an indexable tool holder, a handle, and means to turn the tool holder through a 1/4 turn each time the handle is rotated in either direction substantially a complete turn, the arrangement being such that the tool holder will rotate in the same direction as the handle.

Yet another object of this invention is to provide a device of the character described in which the handle is near the operator and away from the tools on the turret and in which the handle is provided with a hand grip disposed above the

plane of the tool turret, whereby to prevent the tools on the turret from contacting the hands of the operator, thereby making the device safe to use.

5 Still a further object of this invention is to provide a strong, rugged and compact device of the character described which shall be relatively inexpensive to manufacture, easy to assemble, smooth and positive in operation, and yet practical and efficient to a high degree in use.

Other objects of this invention will in part be obvious and in part hereinafter pointed out.

The invention accordingly consists in the features of construction, combinations of elements, 15 and arrangement of parts which will be exemplified in the construction hereinafter described, and of which the scope of application will be indicated in the following claims.

In the accompanying drawings, in which is 20 shown one of the various possible illustrative embodiments of this invention,

Fig. 1 is a side elevational view of an automatic tool block embodying the invention with parts broken away and in cross-section;

25 Fig. 2 is a top plan view thereof;

Fig. 3 is a cross-sectional view taken on line

7—7 of Fig. 3; and

Fig. 8 is a cross-sectional view taken on line

8—8 of Fig. 3.

Referring now in detail to the drawings, 10 designates an automatic tool block embodying the invention. The same comprises a base 11. Said base is formed with a recess 12 at its underside providing side walls 13, a front wall 14, and a rear wall 15. Said front and rear walls comprise flanges formed with countersunk through 15 openings 16 communicating with aligned longitudinal grooves 17 formed on the underside of said walls. The grooves 17 are adapted to register with the T-slots 18 in the cross slide 19 on which device 10 is mounted. Said front and rear walls are furthermore formed with vertical, screw threaded openings 20 extending upwardly from the underside thereof and disposed adjacent the openings 16 and likewise communicating with the grooves 17.

55 Said base 11 furthermore comprises a horizon-

tal wall 22, and an upwardly extending wall 23 having side portions 24, and a curved front portion 25. Said top wall 22 is formed with a recess 26 in its top adjacent the rear end thereof and with a circular boss 27 extending upwardly from said recessed surface. The boss 27 is formed with an annular undercut groove 28 below the upper surface thereof, said groove having an upwardly and outwardly inclined upper surface 30. Extending upwardly from the boss 27 is an axial sleeve 31. The wall 22, boss 27, and sleeve 31 are formed with an axial through opening 33. The wall 22 is also formed with a vertical through opening 34 extending through the recessed surface 26 thereof and disposed on the longitudinal axis of the base. 10

Said wall 22 is formed with another vertical through opening 35 similar to opening 34 and likewise on the longitudinal axis of the base. Said wall 22 is formed with shallow annular bosses 34a and 35a on the underside thereof at the openings 34 and 35, respectively. 20

Said wall 22 is furthermore formed with a shallow boss 33a on the underside thereof at the lower end of opening 33. 25

The wall 22 is also formed with a vertical through opening 36 disposed on the longitudinal axis of the base and located between the openings 34 and 35. 30

Adjacent the front end of the base, wall 22 has a recess 37 of greater depth than the recess 12, forming a thinned wall 38. The wall 38 is formed with a vertical through opening 39, likewise located on the longitudinal axis of the base. At the lower end of said opening is an annular boss 39a. 35

Attached to the underside of the flanges 14 and 15 are base aligning keys 41, received within the grooves 11 and projecting into the groove or slot 18 of the cross slide. The keys 41 are formed with through openings 42 to receive screws 43 passing through the registering openings 16, 42. The lower ends of said screws are screwed to base clamping nuts 45 within slot 18. The keys 41 are attached to the flanges 15 by screws 44 engaged within the screw threaded openings 20 and passing through appropriate openings in the keys. 40

The wall 22 is formed with a vertical through opening 46 disposed in a vertical plane passing through the axis of opening 33 and disposed at right angles to the longitudinal axis of the base. Said wall 22 is furthermore formed with a longitudinal slot or recess 46a at its underside parallel to a side wall 13 and communicating with the lower end of the through opening 46, and also with recess 37. 50

Rotatably mounted on the base is an indexible tool holder 47. Said tool holder is shown in the drawings, for the purpose of illustration, as square. It has a socket 48 rotatably receiving the sleeve 31. Said tool block or tool holder 47 is formed with a through opening 49 co-axial with the socket 48. The tool holder is formed on four sides thereof with grooves 50 to receive tools adapted to be clamped in position by screws 54 in the usual manner. 55

The tool holder 47 is provided at the lower end thereof with an annular boss 52 formed with an annular groove 53 having a downwardly and outwardly inclined lower surface 54. The boss 52 is complementary to the boss 27 and registers therewith for the purpose hereinafter appearing. 70

Said tool holder is furthermore formed on the

underside thereof with four annular sockets 56 equally spaced apart and each disposed adjacent the middle of one side of the tool holder. The sockets 56 are disposed in planes at right angles to each other and passing through the axis of said tool holder and perpendicular to the sides of said tool holder. Said tool holder is furthermore formed with narrow vertical through openings 58 co-axial with the sockets. Said through openings are screw threaded at their upper ends as at 59. 10

Within each socket 56 is a lock pin socket washer 60 formed with a central opening and contacting the upper surface of the socket. Fitted within each socket is a lock pin bushing 61 having a tapered lower surface 62. Screwed within the upper end of each opening 58 is a set screw 63. By removing set screws 63, the washers 60 and bushings 61 may be knocked out of the sockets 56. 15

Extending through the registering openings 33 and 49 in the base and tool holder is a vertical shaft 70. Screwed to the lower end of shaft 70 is a nut 71 and screwed to the upper end of said shaft is a cap nut 72. Interposed between the cap nut 72 and the tool holder 47 is a washer 72a. The shaft 70 is keyed to the tool holder by a key 73. 20

It will now be understood that rotation of the shaft 70 will cause the tool holder to rotate. 25

Means is provided to rotate shaft 70 and hence the tool holder. To this end there is mounted on the shaft 70 adjacent the lower end thereof a gear 75 held on the shaft by the nut 71 and a washer 71a interposed between the nut and said gear. The gear may be keyed to the shaft by a key 76. Received within the vertical opening 34 in wall 22, is a vertical gear stud 77 having a head 78 at its lower end. The stud 77 is formed with an annular groove 79. The base 10 is formed with a horizontal opening 80 extending at right angles to the longitudinal axis of the base and communicating with opening 34. The inner end of the opening 80 is screw threaded as at 81 to receive a set screw 82 to engage groove 79 and hold the stud 77 on the base. On the enlarged lower end of the stud 77 is rotatably mounted a gear 83 meshing with the gear 75. 30

Fitted within the opening 35 is another stud 77a similar to stud 77 and likewise formed with a flat head 78a at its lower end and with an annular groove 79a. 35

The base 22 is formed with a horizontal opening 80a parallel to opening 80 and communicating with opening 35. The inner end of opening 80a is screw threaded as at 81a to receive a set screw 82a adapted to engage within the groove 79a of stud 77a to hold the stud in place. Rotatably mounted on the lower enlarged end of stud 77a is a gear 85 meshing with the gear 83. Said gear 85 is formed at four equally spaced apart points with circular notches 86. Each notch is cut in the outer ends of a pair of teeth 87 as shown in the drawings. The notches are curved for the purpose hereinafter appearing. 40

Rotatably mounted within opening 39 of the base is a vertical lever shaft 88 having a reduced portion 88a adjacent its lower end. Extending downwardly from the reduced shaft portion 88a is a screw threaded portion 89 on which is screwed a nut 90. 45

Mounted on the lower end of shaft portion 88a and keyed thereto is an intermittent or segmental pinion 92. Said pinion 92 is formed with a

segmental, smooth curved portion 93 and with a segmental gear toothed portion 94. The radius of curvature of portion 93 is similar to the radius of curvature of the notches 86. The pinion 92 is keyed to shaft portion 88a as illustrated. The number of teeth in the toothed portion 94 of the pinion 92 is sufficient to rotate gear 85 through an angle of 90°.

It will now be understood that a Geneva gear construction is provided and that each time shaft 88 is rotated 360° gear 85 makes one-quarter of a turn. The number of teeth in the gears 85 and 75 is similar so that each time gear 85 makes one-quarter of a turn, gear 75 likewise makes one-quarter of a turn.

Thus rotation of the shaft 88 through an angle of 360° in either direction will cause the tool holder 47 to rotate through an angle of 90°.

Means is provided to lock the holder in each of its four indexed positions. To this end there is slidably mounted in opening 46, a locking pin 95 having a tapered upper end. The locking pin 95 is adapted to be moved upwardly in the manner hereinafter disclosed, to selectively engage within the bushings 61.

There is provided means for moving the locking pin 95 downwardly to release the holder before rotating the holder from one index position to another, and to again move said locking pin upwardly to locking position after the holder has been rotated to a new index position. To this end the base 11 is formed with a horizontal opening 100 extending to opposite sides of the slot 46a and located about midway between openings 33 and 39. Inserted within said opening 100 is a pivot pin 101 traversing said slot. Pivot pin 101 has an annular groove 101a. Base wall 22 has a vertical hole 101b receiving a set screw 101c engaging groove 101a to hold pin 101 in place. Pivotally mounted on said pin 101 is a lever 102, located in slot 46a. Said lever 102 has a front arm 103 and a rear arm 104. The rear arm 104 is received in a notch 105 at the lower end of the locking pin 95. Thus rotation of the lever 102 in a counterclockwise direction will raise the locking pin 95, whereas rotation of the lever in a clockwise direction will lower the locking pin.

On the shaft portion 88a and keyed thereto is a cam disc 107. Said disc 107 is located above gear 92 and is formed on the upper side thereof with a cammed portion 108 extending through about an angle of 270°; the opposite ends of said cam being ramped downwardly as at 108a and 108b.

A plane passing through the axis of shaft 88 and bisecting the segmental portion 93 is disposed at right angles to a plane passing through the axis of said shaft and bisecting the angle between the ramp ends 108a, 108b of the cam 108.

The front end 103a of lever arm 103 projects downwardly onto the cam disc. The shaft 88 can thus rotate about 45° in either direction before the lever is raised by either ramp 108a or 108b. However, gear 85 will not begin to rotate until shaft 88 has been rotated through an angle of about 90° in either direction so that the lever is rotated to lower the locking pin 95 and release the tool holder before said holder begins to rotate. After the locking pin has been lowered to release the holder, the shaft may be rotated through an angle of about 270° while the locking pin is held down and portion 103a of the lever rides on the dwell portion 108 of the cam. During this angle of rotation the holder is rotated through an angle of 90°. Thus the locking pin is moved up

into locking position after the tool holder has been rotated through an angle of 90° from one index position to another index position, and this is true whether the shaft is turned in one direction or the other.

The lever is retained in contact with the cam by means of a spring pressed plunger 110 slidably mounted in an opening 111 in the base and described in greater detail hereinafter.

10 Mounted on the base is a cover 114 which is attached to the base by means of a plurality of screws 115. The cover 114 is formed with a socket 116 on its underside registering with opening 111 in the base. Said cover is also formed 15 with a through opening 117 of reduced diameter communicating with said socket. The stem of the plunger 110 passes through the opening 117. A spring 118 on the stem of the plunger is interposed between the head thereof and the upper end of the socket 116, as illustrated in Fig. 1 of the drawings. The plunger thus engages the lever and keeps it in contact with the cam disc.

Means is provided to clamp the tool block in each of its index positions to prevent chatter. 20 To this end there is provided a brake clamp 120 comprising a pair of substantially similar symmetrical brake parts 121 each having a semi-cylindrical portion 122 and a lug 123 at the rear end thereof. One lug 123 is formed with a countersunk through opening 124, whereas the other lug 123 is formed with a screw threaded through opening 125. Extending through the countersunk through opening 124 is a screw 126 screwed within the opening 125. Screw 126 serves to adjust the break.

At the front ends of brake or cam portions 121 are parallel, symmetrical extensions 130 having inwardly and forwardly inclined outer surfaces 131. On the inner surfaces of the extensions 40 130 are registering sockets 132 receiving a spring 133 interposed between said extensions and normally urging the brake portions 121 apart to release the holder. The brake portions 121 surround the complementary bosses 21 and 52 of the base and holder respectively. Said brake portions are formed on the inner surfaces thereof with grooves 134 having inclined top and bottom surfaces engaging the surfaces 54 and 30 of the holder and base respectively.

On the outer side of each of the lugs 130 is embedded a vertical pin 136 projecting beyond the inclined surface 131. At the outside of lugs 130 and spaced therefrom are parallel lugs 140. Slidably mounted on the base is a clamp actuating member 141 having a bifurcated arm 142 received between the lugs 130 and 140, and having forwardly and inwardly inclined surfaces 143 adapted to engage the pins 136. Member 141 is slidably mounted between the wall portions 24 of the base.

It will now be understood that as member 141 moves to the right, looking at Fig. 4 of the drawings, it will draw the brake portions 121 together to tightly grip the holder and clamp it to the base. However, as member 141 moves to the left or forwardly it will release the brake portions 121, which are then separated by the spring 133 to release the holder. Mounted on the shaft 88 and keyed thereto is a cam 145 adapted to engage the forward end of member 141, for moving member 141 to the right, to clamping position.

Means is provided to retract member 141 when the cam is moved to the right or left from the position shown in Fig. 4 of the drawings. To

this end cam slide member 141 is formed with a longitudinal slot 148. Fixed within opening 36 and extending upwardly therefrom is a pin 147 extending upwardly above the base and into slot 148. The upper end of 147a of pin 147 is semi-cylindrical and has a flat front face. Interposed between the flat face of pin portion 147a and the front end of the slot 148 is a compression spring 150. The spring 150 normally tends to retract the cam slide 141. The cam 145 can be moved beyond the dead center position of Fig. 4 in either direction.

It will now be understood that as shaft 88 is rotated either to the right or left from an index position the slide 141 is immediately released and retracted so that the base or clamp opens up or releases the holder at the outset of rotation of said shaft. Furthermore as the shaft nears completion of a full turn the cam again moves the cam slide or actuator 141 to the right to again clamp the holder. Thus the holder is released before the locking pin is released and is again clamped after the locking pin is moved to locking position.

Means is provided to rotate shaft 88. To this end cover 114 is formed with an enlarged recess 160 on the underside thereof and with a vertical through opening 161 communicating with said recess and co-axial with opening 39 in the base 11.

Cover 114 is furthermore formed with an upwardly extending boss 163 formed with a vertical through opening 164 likewise communicating with the recess 160.

Shaft 88 has an upper end portion 165 passing upwardly through opening 161. Journalled in said opening and keyed to shaft portion 165 is a gear 166. Gear 166 may be formed with a flange received within opening 161. Attached to the upper end of the shaft 88 is a cover plate 170. Two of the teeth of gear 166 are formed with a circular notch 171 for the purpose herein-after appearing. It will be noted that gear 166 is located above cam 145.

Rotatably mounted on the cover 114 is a gear member 173 having a vertical stem 174 disposed within vertical opening 164. At the lower end of said stem is a segmental gear portion 176 located on top of member 141. Gear 176 has a smooth segmental portion 177 adapted to be received within the notch 171 of gear 166. Said gear 176 is furthermore formed with teeth 178 adapted to mesh with the teeth of said gear 166. Gear 176 has sufficient teeth to rotate gear 166 through one complete revolution every time member 173 is rotated substantially one revolution. Due to the smooth portion 177 there is a lost motion or an angle through which member 176 may be rotated without affecting gear 166. The angle or zone of free motion may be varied as desired.

Stem 174 has a portion 180 extending above the boss 163. Mounted on said portion 180 is a handle 184. Handle 184 has a hub 185 formed with a vertical through opening to receive portion 180. Said handle 184 is keyed to stem portion 180 by means of a key 186. Attached to the upper end of stem portion 180 is a retaining plate 187. Handle 184 is inclined upwardly and rearwardly from hub portion 185. At the upper end thereof is an enlarged portion 190 formed with a central opening 191. Within said opening 191 is a sleeve 192. Journalled within the sleeve is a member 193, having a screw threaded portion 194 at its upper end.

Screwed to said screw threaded portion is a

ball 195 adapted to be grasped by the hand of the operator. The ball 195 may be fixed in place by a taper pin. Member 193 may be retained by sleeve 192 by means of a split ring or in any other suitable manner.

Due to the upward inclination of handle 184, ball 195 is located above the tool holder. The hand of the operator grasping the ball will thus be clear of the tool holder, thereby preventing the possibility of injury to the operator's hand.

The operation of the device will now be understood. To rotate the tool holder through an angle of 90° in either direction the ball 195 is grasped by the operator and rotated substantially one turn in either direction.

It will be noted that the tool holder will rotate in the same direction as the handle, so that if the handle is rotated in a clockwise direction the tool holder will likewise be rotated in a clockwise direction. If the handle is rotated in a counterclockwise direction the tool holder will likewise be rotated in a counterclockwise direction. It is not necessary to rotate the handle exactly through an angle of 360°, due to the fact that there is a lost motion or free zone of rotation for the handle. The operator can therefore quickly turn the handle and does not have to be careful about the point of beginning or the end point of rotation of the handle as long as he starts and ends within the free zone.

As the handle is rotated substantially one turn, the tool holder will be rotated through a 1/4 turn. During the rotation of the handle, the clamp or brake is first released, the locking pin is then lowered or disengaged from the holder, the holder is then rotated through an angle of 90° making a 1/4 turn, the locking pin is then again lifted to index the holder, and then the clamp or brake is again actuated to clamp the holder in the new index position.

It will be noted that the handle may be moved either in a clockwise or counterclockwise direction and the various mechanisms will go through the sequences, and such operation is due to the fact that cam 145 operates in either direction from dead center.

It will thus be seen that there is provided a device in which the several objects of this invention are achieved, and which is well adapted to meet the conditions of practical use.

As various possible embodiments might be made of the above invention, and as various changes might be made in the embodiment above set forth, it is to be understood that all matter herein set forth or shown in the accompanying drawings is to be interpreted as illustrative and not in a limiting sense.

Having thus described our invention, we claim as new and desire to secure by Letters Patent:

1. A device of the character described, comprising a base, a tool holder mounted for rotation on the base about a vertical axis, said tool holder having a plurality of angularly spaced sockets, a locking pin on said base adapted to selectively engage said sockets, a lever pivoted medially the ends thereof on said base and having one arm engaging the locking pin, a vertical shaft rotatably mounted on the base, a cam on the shaft adapted to engage the other arm of the lever, a segmental gear on said shaft, a gear fixed to the tool holder for rotation therewith, gearing interposed between said segmental gear and the gear fixed to the tool holder, a second gear on said shaft, a segmental gear adapted to mesh with

the second gear on said shaft, and a handle fixed to said last-mentioned segmental gear.

2. A device of the character described, comprising a base, a tool holder mounted for rotation on the base about a vertical axis, said tool holder having a plurality of angularly spaced sockets, a locking pin on said base adapted to selectively engage said sockets, a lever pivoted medially the ends thereof on said base and having one arm engaging the locking pin, a vertical shaft rotatably mounted on the base, a cam on the shaft adapted to engage the other arm of the lever, a segmental gear on said shaft, a gear fixed to the tool holder for rotation therewith, gearing interposed between said segmental gear and the gear fixed to the tool holder, a second gear on said shaft, a segmental gear adapted to mesh with the second gear on said shaft, a handle fixed to said last-mentioned segmental gear, said handle extending upwardly, and a hand grip ball rotatably mounted on the outer end of said handle.

3. A device of the character described, comprising a base, a tool holder mounted for rotation on the base about a vertical axis, said tool holder having a plurality of angularly spaced sockets, a locking pin on said base adapted to selectively engage said sockets, a lever pivoted medially the ends thereof on said base and having one arm engaging the locking pin, a vertical shaft rotatably mounted on the base, a cam on the shaft adapted to engage the other arm of the lever, a segmental gear on said shaft, a gear fixed to the tool holder for rotation therewith, gearing interposed between said segmental gear and the gear fixed to the tool holder, a second gear on said shaft, and a second gear adapted to mesh with the second gear on said shaft, and handle means to rotate said second segmental gear.

4. A device of the character described, comprising a base, a tool holder mounted for rotation on the base about a vertical axis, said tool holder having a plurality of angularly spaced sockets, a locking pin on said base adapted to selectively engage said sockets, a lever pivoted medially the ends thereof on said base and having one arm engaging the locking pin, a vertical shaft rotatably mounted on the base, a cam on the shaft adapted to engage the other arm of the lever, a segmental gear on said shaft, a gear fixed to the tool holder for rotation therewith, gearing interposed between said segmental gear and the gear fixed to

the tool holder, a second gear on said shaft, and a second segmental gear adapted to mesh with the second gear on said shaft, said second segmental gear having a zone of free movement without moving said second gear and provided with means to prevent movement of said second gear while said second segmental gear is in said free zone, and handle means to rotate said second segmental gear.

- 10 5. A turret indexing device comprising a rotatably mounted turret, a first shaft, a handle on said shaft, a mechanism operated by said shaft for step by step indexing of the turret and locking of the turret after each indexing step, and 15 unlocking of said turret before each indexing step, said mechanism being so constructed and proportioned that said step by step movement of said turret in one direction is accomplished by continuous rotation of said handle and shaft 20 in one direction, and step by step movement of the turret in an opposite direction is accomplished by continuous rotation of said handle and shaft in an opposite direction, and a single step indexing of the turret is accomplished by rotation of 25 the handle through less than a revolution, the remaining portion of said revolution being a free zone of movement, said mechanism including a second shaft, and means operatively connecting said second shaft and said turret to successively 30 unlock the turret, index the turret and again lock the turret, and intermittent gearing connecting said first and second shafts, said intermittent gearing comprising a gear on the second shaft having teeth all around its circumference, and 35 a gear on the first shaft having teeth around a major portion only of its circumference interengaging the teeth of the gear on the second shaft, rotation of said handle during the portion of revolution where the teeth of the gear on the first 40 shaft meshes with the teeth of the gear on the second shaft being adapted to index the turret one step, and the remaining portion of the circumference of the gear on the first shaft being so constructed that during the free zone of movement 45 of the handle, the gear on said first shaft is ineffectual to rotate the second shaft, whereby said handle starts from any position in the free zone and ends in any position in the free zone in order to successively unlock the turret, index 50 the same, and then again lock the turret.

SECONDO L. CASELLA.
MORRIS G. HIMOFF.
